UNITED STATES PATENT OFFICE

101,372

DESIGN FOR A GLASS BUILDING BLOCK

Edward P. Lockart, Jr., Muncie, Ind., assignor
to Owens-Illinois Glass Company, Toledo,
Ohio, a corporation of Ohio

Application January 31, 1936, Serial No. 60,926

Term of patent 14 years

To all whom it may concern:

Be it known that I, Edward P. Lockart, Jr., a citizen of the United States and residing at Muncie, in the county of Delaware and State of Indiana, have invented a new, original, and ornamental Design for a Glass Building Block, of which the following is a specification, reference being had to the accompanying drawing forming a part thereof.

In the drawing:

Fig. 1 is a perspective view showing particularly one face of a hollow glass building block embodying my design.

Fig. 2 is a perspective view of the other face showing a reversal of the application of the decorations.

Fig. 3 is a sectional view taken along the line 3—3 of Fig. 2 intended to emphasize the rib arrangement involved in producing my design.

I claim:

The ornamental design for a glass building block substantially as shown and described.

EDWARD P. LOCKART, JR.
